UNITED STATES PATENT OFFICE.

ALEXANDER D. ELLIOTT, OF VIOLA, ILLINOIS.

CONVERTIBLE FURNITURE.

1,249,932.

Specification of Letters Patent. Patented Dec. 11, 1917.

Application filed July 22, 1915. Serial No. 41,283.

To all whom it may concern:

Be it known that I, ALEXANDER D. ELLIOTT, a citizen of the United States, residing at Viola, in the county of Mercer and State of Illinois, have invented certain new and useful Improvements in Convertible Furniture, of which the following is a specification.

The present invention relates to improvements upon the convertible furniture shown in my Patent No. 1,120,701 granted to me December 15, 1914, and in my application for patent Serial No. 11,938 filed March 5, 1915. The subject matter of such patented application is an article of furniture which comprises a relatively stationary frame and members movable relative thereto which in one position form with the stationary frame a comfortable and convenient chair or settee and in another position a comfortable and substantial bed or mattress support. In the construction of said prior application the bed is formed in part of a section or frame pivoted to the front of the stationary frame and adapted to swing outwardly to form the foot of the bedstead, in which position it is supported by a member pivoted thereto which in the closed position of the article forms the seat and arms of the chair. The bed or mattress support comprises in addition to the swinging section an intermediate member pivoted thereto and supported thereby, and a third or head section pivoted to the intermediate section and supported at its free end by the main frame in horizontal position when the article of furniture is open. The main frame is formed with guides which, when the article of furniture is closed guide the free end of the bed section upward to permit the swinging section to be closed with the movable bed sections concealed between the same and the stationary frame. My present improvements have for their purpose increasing the rigidity of the construction without an increase in the weight thereof, securing greater comfort when the article is used either as a chair or settee or as a bed, improving the appearance of the article and increasing the convenience and ease of manipulating the same.

In the accompanying drawings and following specification, I have shown and described in detail a preferred form of my invention. It is to be understood, however, that the specific disclosure is for the purpose of exemplification only and that the scope

of my invention is defined in the following claims in which I have endeavored to distinguish it from the prior art so far as known to me without, however, relinquishing or abandoning any portion or feature thereof.

In the drawings, Figure 1 is a vertical longitudinal section through the main frame just within the near side frame thereof showing the movable parts in elevation, the article being extended for use as a bed; Fig. 2 is a similar view with the article folded and in condition for use as a chair or settee, a part being shown in section to better disclose the interior construction; Fig. 3 is an enlarged vertical section on the line 3—3 of Fig. 4 of a detail showing the parts in the position which they occupy when the article is used as a bed; Fig. 4 is a transverse vertical section upon the line 4—4 of Fig. 1, a part, however, being shown in similar section upon another plane; Fig. 5 is a horizontal section upon the line 5—5 of Fig. 1 looking downward in the direction of the arrows; Fig. 6 an enlarged vertical section upon the line 6—6 of Fig. 5 looking in the direction of the arrows; Fig. 7 a section upon the line 7—7 of Fig. 5 looking in the direction of the arrows; Fig. 8 a horizontal section upon the line 8—8 of Fig. 1 looking downward; Fig. 9 a transverse vertical section on the line 9—9 of Fig. 8; Fig. 10 is an enlarged detail in vertical section upon the line 10—10 of Fig. 2; Fig. 11 a vertical section of said detail upon the line 11—11, of Fig. 10, parts being shown in elevation and Fig. 12 a horizontal section upon the line 12—12, of Fig. 10.

The same reference numeral is applied to each part wherever it occurs throughout the several views.

Preferably the frame of my improved article of furniture is made throughout of metal, though parts thereof may be made of other material as desired. As shown the material chiefly employed for the frame is angle-iron which has the advantage of great strength for the weight of metal employed. The stationary frame consists of two side frames each comprising upper and lower horizontal members 13, 14, front and rear vertical members or corner posts 15, 16, and inclined struts 17 all formed of angle iron, the last named being bent near its upper end at 18 to form the top section 19 and the inclined rail 20 which is fastened to the

lower horizontal member at 21. The side frames are connected together by rear cross pieces 22, 23, at the top and bottom thereof respectively, front cross pieces 24 and 5 diagonal braces 25, 26, the last-named being best shown in Fig. 5. The side rails 14, 14, rear and front rails 23, 24, and diagonal braces 25, 26, form the base of the stationary frame and are secured together in position 10 by casting iron or other metal about the joints thereof as shown more particularly in Fig. 6. The corner joints of this frame are formed by iron castings 27 which are preferably made by inserting the strips or angle 15 irons to be united in a suitable mold after first perforating them as at 28, 29, 30, and casting the uniting metal about them, which, as it flows into the perforations in the rail ends and also shrinks on cooling, firmly 20 unites the strips together. The rear castings 27^a are also formed with sockets 31 into which liners 32 may be cast or inserted for the purpose of receiving casters 33. The similar forward castings 27^b are not formed 25 with caster sockets but the side rails are extended forwardly beyond said castings and the front rails 24 and connected to front posts or uprights 15 by somewhat similar castings 27^c in which are formed the sockets 30 for the front casters. The castings 27^b in addition to the front and side rails and diagonal braces secure the lower ends of uprights 35 which are secured at their upper ends to the upper horizontal side rails of the 35 chair. The braces 25, 26, are preferably secured together at their centers by a casting 36. In making these corner castings the bottom and vertical rails are preferably all assembled with their meeting ends inserted in 40 molds in which the castings are to be made and the molds are then teemed in the usual manner. By this means I secure a frame of unusual rigidity and accuracy at a relatively low cost. Except where the castings are 45 made as above described, the structural steel is riveted or otherwise secured together.

To the uprights 35 upon opposite sides of the chair are secured attaching plates 37 which are formed at their upper and lower 50 forward corners with ears 38, 39, to the lower of which are pivoted the elbow members 40 of the swinging frame 41 of the bed. A panel between the elbow members forms part of the front of the chair when closed. 55 The swinging frame comprises in addition to the elbow members on opposite sides thereof a substantially rectangular frame 42 of angle iron, the side rails 43 of which are riveted at 44 to the upper ends of the elbow 60 members and extend rearwardly past the same at 45 and are connected at their rearward ends by struts 46 to the elbow members 40 whereby rigid connections between said elbows and frame are formed. The 65 frame 42 is upwardly bent at 47 to form a

foot for the bed and is provided on its upper side, speaking with reference to the extended position of the article, with a suitable wire or other mattress support and on its under face and the outside of the upwardly-bent 70 portion with upholstery 48 which, when the device is folded to form a chair, forms the back of the latter. The elbow members are suitably braced as for example by the corner pieces 49 and preferably connected by suitable cross pieces to increase the rigidity of the construction. 75

In order to assist in opening and closing the chair, tension springs 50 are connected at one end to the upper ears 38 of the attaching plates 37 and at the other to holes 51 in the struts 46, the construction being such that the spring is under tension tending to close the article of furniture in the position shown in Fig. 1 and under tension 85 tending to open the article when the latter is closed as shown in Fig. 2.

Additionally to the first section 42 the mattress support comprises an intermediate section 52 and a bodily movable head section 53, the former being pivoted directly to the foot section and the latter to the intermediate section. The intermediate section comprises a rigid boxing which may be formed of angle iron but preferably comprises sheet metal ends 54 and transverse rails or angle irons 55, 56, connecting the same at their lower corners. In addition to said transverse rails the bottom of the boxing is formed or provided with braces 57 which may be extended diagonally or otherwise and form a bottom for the boxing in addition to strengthening the same for a reason which will presently appear. 90

The side rails of the frame 42 are extended beyond the struts 46 heretofore described to form ears 58 which are suitably pivoted to the upper forward corners of the end plates of the boxing and thereby support the latter, said end plates being inwardly 105 flanged as at 59 (Fig. 8) to provide broad bearing surfaces against the faces of the angle iron struts 46, the location of the pivot with reference to said surface being such that the boxing is strongly supported with 110 its upper edges in the plane of the foot section of the bed when the latter is extended. Preferably the end plates are fitted with outwardly-projecting beading 60 with tapered ends which serves to protect the pivots 115 and faces of said ends from scraping when the furniture is closed or opened. Through the upper rear corners of the end plates of the boxing are pivoted the side rails of the head section 53 of the mattress support, said 120 rails being connected at their free ends by a suitable transverse rail to form a frame. Upon the outer faces of the side rails of the head section 53 at their free ends are mounted 125 rollers 61 which rest upon the ledges 130

formed by the horizontal wings of the upper horizontal members 13 of the main frame when the bed is extended. Inclined angle irons 62 are connected at one end to the 5 rails 13 and at their other end to the vertical rails 16 of the stationary frame, the angle of inclination being such that rearward pressure upon the head bed section causes the rollers 61 to travel up said inclines to fold 10 said section into a substantially vertical position, it being understood that after leaving the inclined guide 62 the rollers move up the flanges of the vertical post 16.

The action of the bed as thus far described in folding is that the hinged foot section being raised the intermediate section at first maintains its position relative to the latter but the head section, due to the guides 62, begins to turn upward toward 20 a vertical position. As the folding proceeds gravity causes the boxing or intermediate bed section to turn with relation to the foot section so that the parts ultimately reach the position shown in Fig. 2 with the boxing 25 substantially horizontal and the head section vertical.

The arms and seat of the chair comprise a rigid member which is so pivoted to the upholstered side of the foot section as to 30 rest upon the upper horizontal rails of the stationary frame when the article is folded to serve the usual purpose, and to swing forward under the foot section when the bed is extended to form a support therefor. This 35 seat member comprises a generally rectangular frame of angle iron having end rails 63 connected by suitable cross rails indicated in dotted lines at 64, front and rear legs 65, 66, and supports arranged at opposite ends 40 thereof and comprising vertical iron strips or rods 67 and inclined strips or rods 68, the latter of which carry at their upper ends pivots 69 by which the frame is attached to the swinging foot section of the bed. The 45 pivots 69 coöperate with plate brackets 70 riveted or otherwise secured to the side rails of the bed section and formed with notched bearings (see dotted line, Fig. 3) to receive the pivots. Upon each bracket is pivoted at 50 71 a plate 72 which at one end is formed with a rounded notch or hook 73 which in one position of the plate forms with the bearing notch in the bracket a substantially circular opening in which the corresponding 55 pivot of the seat frame fits. The other end 74 of the pivoted plate is formed with a boss or projection which is adapted to spring into a depression 75 in bracket 70 (see Fig. 14), to normally maintain the swinging 60 plate in the position in which it retains the seat pivot in the bearing. Thus the seat frame is normally pivoted to the foot section of the bed but may be readily released therefrom by simply turning the pivoted 65 locking plates holding the pivots of said

frame in position. The seat proper may be mounted upon the seat frame in any suitable or well-known manner and may be either permanently attached to or detachable therefrom. The arms constitute housings for the supporting irons 67, 68, and may be built of wood or metal or partly of wood and partly of metal as desired and upholstered in any desired shape, the housings, however, having openings in the rear 70 thereof which are entered by the bracket plates to make the connection with the seat supports. Obviously, the arms may be stripped from said supports, if detachably secured to the frame by merely releasing 80 the fastenings and lifting the arms off. Said arms, however, should be broad and substantial enough to form a suitable support upon which the bed section may rest. The angle between the rear faces of the 85 arms and the bottom of the seat member is such that when the article is folded with the seat frame resting upon the upper horizontal rails of the main frame the arms fit snugly against the foot section of the bed 90 which then forms the back of the chair or settee and in order to brace the foot section or back firmly in closed position I form openings 76 (see dotted lines in Fig. 1) near the front end of said horizontal side rails 95 into which project tapered lugs 77 secured to the bottoms of the side rails of the seat frame, the taper of said lugs being such that as the seat comes to final position on the main frame they exert a wedging action 100 to press the foot section or back firmly against the inclined rails of the stationary frame. Because of the engagement of said lugs with the sides of the stationary frame the seat frame forms a brace for the latter 105 and prevents any tendency to spread or collapse.

In order to maintain the article locked in closed position I provide an engagement between the stationary frame and the seat by 110 which the two may be secured together and released only when desired. For this purpose the seat member is provided with a latch which may be mounted upon one or both of the arms or upon the front of the 115 seat or elsewhere as desired and the main frame is provided with a stationary catch plate to receive the latch. As shown in the drawings, the latch is mounted just below the seat within panel 77^a attached to the seat 120 which coöperates with a panel upon the upright portions of the elbow irons, as seen in Fig. 2, to mask or conceal the interior mechanism of the chair. The latch is illustrated on an enlarged scale as heretofore stated in 125 Figs. 10, 11 and 12, the latch proper 78 being pivoted on said panel at 79 and extending inwardly and downwardly and engaging the plate 80 which may be connected in any suitable manner with the stationary frame 130

and extends upwardly between the elbow members 40. The latch is normally maintained at its upward limit of movement by a compression spring 81 engaging a lug 82 projecting at right angles from the short arm 83 of said latch as best seen in Fig. 12. In order to release the latch a plunger 84 is mounted to slide in a hole 85 in the panel and guided at its rear end by a U-shaped bracket 86, said plunger being provided with an annulus 87 adjustably secured to the plunger by set screw 88, and arranged to engage lug 82 when the plunger is forced outward. Spring 89 between said bracket 10 and annulus forces the plunger outwardly when it is not held inward by the dog to be now described. The plunger 84 is formed with a shoulder 90 (see Figs. 10 and 11) and the dog 91 is slidingly mounted upon 15 the inner face of the panel as by means of slot 92 and screw 93 so that it may engage with or be disengaged from the shoulder on the plunger; and a spring 94 contained in a recess 95 in said panel engages a lug 96 20 struck up from said dog and normally forces the latter downward into engagement with the plunger so that when the latter is thrust inward the dog engages the shoulder above-mentioned and maintains the plunger in 25 inner position until said dog is pressed upward. Then the pressure of the spring 89 referred to above will force the plunger outward. The plunger extends through the outer face of the panel and is formed with a 30 handle 97 which may be grasped in opening the furniture after the latch has been released as above described. Preferably the handle takes the form of a button which when in the inner position appears merely 35 as an ordinary form of ornament upon the chair. By means of these handles the seat member may be raised sufficiently to withdraw the lugs 77 from the slots in the main frame and then the seat structure is drawn 40 forward, the foot section of the bed and the other sections following, until finally the seat member rests upon its legs and the foot section upon the seat member.

Each of the bed sections may be provided 45 with any usual or desired metal or other mattress supporting fabric but it is more desirable and perfectly feasible to stretch a continuous piece of such fabric from head to the foot of the bed and preferably I employ a well-known fabric of this character 50 having longitudinal bands of steel which are sufficiently pliable and resilient to bend to the extent necessary in folding the chair without injury. Between the cross pieces or 55 braces of the box section and the mattress supporting fabric I preferably interpose coiled springs since said box is at the location where the heaviest weight is received 60 and where it is customary to reinforce the

spring fabric. These springs are best shown 65 in Figs. 8 and 9 at 98 and may, if desired, be secured to the bottom of the boxing though this is not essential because of the narrow limits of the box.

As before observed, the rear end of the 70 head section is free and may be raised. In order to support it in raised position I provide a pair of straps 99 which are attached near the upper ends of the side frames on opposite sides of the stationary frame, and 75 formed with holes or slits to receive buttons 100 upon the ends of the side rails of the bed. To provide a plurality of positions a number of slots may be formed in the straps which may be of leather or other suitable 80 material.

I claim:

1. In an article of the class described, a stationary frame, a swinging frame pivoted to the lower front corners of the stationary 85 frame comprising a bed section adapted to form a back for the chair when folded, a panel near the inner or pivoted end of the swinging frame and adapted when the frame is in closed position to form a portion of the 90 front of the chair and a seat member pivoted to the swinging frame and adapted when the latter is in closed position to rest upon the stationary frame, and a panel secured to said pivoted seat and adapted to 95 coöperate with the first said panel when the article is in closed condition to cover the front of the chair.

2. In an article of the class described, a stationary frame, a swinging frame pivoted 100 to the front of the stationary frame comprising a bed section adapted in closed position to form a back for the chair, a seat member pivoted to said bed section and adapted to support the foot of the latter 105 when horizontal comprising a frame having side supporting members and brackets upon the swinging frame to which said side supporting members are pivoted.

3. In an article of the class described, a 110 stationary frame, a swinging frame pivoted to the front of the stationary frame comprising a bed section adapted in closed position to form a back for the chair, a seat member pivoted to said bed section comprising 115 a frame having side supporting members and brackets upon the swinging frame to which said side supporting members are pivoted, housings forming arms inclosing said supporting members and forming rests 120 for the swinging section when in open position.

4. In an article of furniture of the class described, a stationary frame, a swinging frame pivoted thereto, brackets on said frame having pivot seats therein, a seat member having supporting members provided with pivots adapted to engage said 125

bracket seats and means on the brackets for maintaining the seat pivoted in operative relation thereto.

5. In an article of the class described, a stationary frame, a swinging frame pivoted thereto comprising a bed and seat-back forming section, a seat member pivoted on said bed section, brackets on the bed section having notches adapted to receive the pivots on 10 the seat member and pivoted hooks adapted to maintain the pivots of the seat member in said notches.

6. In an article of the class described, a stationary frame, a swinging frame pivoted thereto comprising a bed and seat back forming section, a seat member pivoted to said section and adapted to swing forwardly thereunder to form a rest therefor and when the latter is in folded position to rest upon 20 the main frame, a latch on said seat member and a catch plate on said stationary frame adapted to coöperate to maintain the article in closed position.

7. In an article of the class described, a stationary frame, a swinging frame pivoted thereto and comprising a bed and seat back forming section, a seat member pivoted to said section and arranged to rest upon the stationary frame when the article is closed, 25 a latch and catch upon the seat member and main frame respectively for holding the article in closed condition and a spring actuated plunger for releasing said latch and means for normally restraining the movement 35 of the plunger.

8. In an article of the class described, a stationary frame, a swinging frame pivoted thereto and comprising a bed and seat-back forming section, a seat member pivoted to 40 said section and arranged to rest upon the stationary frame when the article is closed, a latch and catch upon the seat member and main frame respectively for holding the article in closed condition and a spring- 45 pressed plunger extending through said seat member to form a handle upon the outside thereof.

9. In an article of the class described, a main frame, a swinging frame pivoted thereto and adapted to fold against the main frame to form a chair and to be extended to form a bed, a seat member pivoted upon the swinging frame and adapted to form a chair therewith and to rest upon 50 the stationary frame, a catch upon the stationary frame, a pivoted latch upon the seat member adapted to engage said catch,

a spring tending to maintain said latch in engagement with the catch, a plunger adapted when moved in one direction to 60 engage and release the latch, a spring for moving it in said direction and a catch plate for maintaining the plunger inoperative.

10. In an article of the class described, a stationary frame, a swinging frame pivoted thereto and adapted in one position to form a support for a bed and in the other position to close against said stationary frame, a second bed section pivotally connected to the first said section and straps secured to the stationary frame and adapted to support said head section in an inclined position.

11. In an article of the class described, a stationary frame, a swinging frame pivoted thereto and comprising a bed section and a seat back on the section, a seat member pivot- 75 ed to said section and arranged to rest upon the stationary frame when the article is closed, a latch and catch upon the seat mem- 80 ber and main frame respectively for holding the article in closed condition and a spring-pressed plunger extending through said seating member to form a handle upon the outside thereof and adapted to engage and 85 release the latch.

12. In a device of the class described, a stationary frame, a swinging frame pivoted thereto and extending substantially the full width of the stationary frame and a seat 90 member pivoted to the swinging member, extending the full width thereof and comprising the seat proper and supports rigid therewith, pivotally connected to the swinging frame and adapted to support the foot 95 of the latter substantially at its side edges.

13. In a device of the class described, a stationary frame, a swinging frame pivoted thereto and adapted to fold against the stationary frame to form a seat back and to 100 swing to a horizontal position to form a bed support, a seat structure comprising the seat proper, arms rigid therewith, said seat structure being pivoted to the swinging frame and adapted when the latter is in closed 105 position to rest upon the stationary frame and when the swinging frame is horizontal to swing forwardly thereunder, the arms of the seat member receiving and supporting the side edges of the swinging member.

ALEXANDER D. ELLIOTT.
